UNITED STATES PATENT OFFICE.

ROLLO R. BELL, OF PASADENA, CALIFORNIA.

INTERNAL-COMBUSTION ENGINE.

1,278,571.

Specification of Letters Patent. Patented Sept. 10, 1918.

Application filed November 9, 1916. Serial No. 130,397.

To all whom it may concern:

Be it known that I, ROLLO R. BELL, a citizen of the United States, residing at Pasadena, in the county of Los Angeles and State 5 of California, have invented new and useful Improvements in Internal-Combustion Engines, of which the following is a specification.

My invention relates to improvements in 10 internal combustion engines and the objects of my improvements are, to provide cylinders on the opposite sides of a crank shaft having the stresses in the operating parts 15 equalized by forming expansion in the cylinder on one side of the crank shaft when the cylinder on the opposite side is under compression; to equalize the stresses in the engine by having the pistons in the opposite cylinders rigidly connected; to generate gas 20 and steam in one and the same cylinder in successive operation; to provide means on the ends of the cylinders by which gas and water can be injected alternately; the invention consisting in the construction, combination 25 and arrangements of devices hereafter more fully described and claimed, and illustrated in the accompanying drawing, in which:

Figure 1 is my device in vertical longitudinal section, one cylinder ready for explosion and the other cylinder ready for compression.

Fig. 2 is my device in vertical longitudinal section, one cylinder under explosion 35 and the other cylinder closing up for compression.

Fig. 3 is the feeding pump which supplies fuel and water to the combustion chamber.

Fig. 4 is my spark plug forming at the 40 same time a timer when used in combination with my internal combustion engine.

Similar numbers refer to similar parts throughout the several views.

The housings 1 and 2 are mounted on the 45 frame 3, the top of the frame forming at the same time the lower guide bar for the piston. Piston-cylinders 5 and 6 are slidably mounted within the housings 1 and 2. The crosshead plates 7 and 8 are suitably secured to the piston cylinders 5 and 6, thereby connecting the piston cylinders on the opposite sides of the crank-shaft 9 rigidly to one body. The inner pistons 10 and 11 are slidably mounted within the piston cylin-

ders, two of the inner pistons, on the opposite sides of the crank shaft forming also one body by the cross-head plates 12 and 13. The upper guide bar 4 connects the housings 1 and 2 on the upper part.

Grooves 15 are provided in the inner surface of the housings 1 and 2 to allow a communication from the housing through the grooves 15 in the housing over to the grooves 16 in the piston-cylinders 5 and 6, and further on through the inlet recess 17 in the 60 housing and the inlet port 18 in the piston-cylinders with the inside of the piston-cylinders.

Normally, the housings form merely air compressors, the air being admitted through 70 suitable inlet valves, not shown in the drawing, at the openings 19. Such construction is especially adapted for a low-gravity fuel oil. The fuel oil is compressed and injected by special pumps 20, attached to the ends of 75 the housings, while the piston rods 21 of such pumps are secured to the piston-cylinders.

A pump of such construction, suitable to inject the fuel oil and water into the device 80 is more clearly illustrated in Fig. 3, the numeral 22 indicating the end plate of the housing on which the cylinder 23 for the pump is formed or to which the cylinder may be suitably attached. The pump piston 85 24 is slidably disposed in the cylinder 23 having the piston rod 25 secured thereto. Conduits 26 and 27 are provided inside of the piston rod 25 communicating with the inside of the piston cylinders. Check valves 28 and 29 are disposed in the pump-piston 90 regulating the communication of the chambers 30 and 31 with conduits to the interior of the piston-cylinders 5 and 6. A connection 32 is provided to allow the attachment 95 of a suitable feeding valve to the chamber 30, preferably for the fuel oil, while another connection 33 is provided to allow the use of water through the chamber 31.

The pitman 34 connects the crank shaft 9 100 with the cylinder pistons 5 and 6, as the cylinder pistons on the opposite sides of the crank shaft are attached together, this causing always the same direction in the movements of the cylinder pistons on opposite sides of the crank shaft. The pitman 35 operates the two inner pistons in a similar manner as these pistons also form one body,

the direction in the movements of the inner pistons being the opposite to the cylinder-pistons.

The operation of my engine is as follows:—

Under the presumption that the engine is turning in the direction indicated by the arrow 36, the gas mixture in the chamber between the inner piston 11 and the cylinder-piston 6, is ready for explosion, see Fig. 1. The inner piston 11 will slide toward the center of the engine, while the cylinder-piston 6 will slide outwardly, the explosion having force until the port 18 in the cylinder piston passes the exhaust 37, such position being illustrated at the left in Fig. 2.

After the waste has escaped through the exhaust as described above, the pistons come to a position as shown at the left in Fig. 1, the inside of the cylinder piston filling again with fresh air through the channels 15, 16, recess 17 and port 18. Completing its cycle the piston cylinder 6 will move toward the center of the engine and the inner piston 11 will move outwardly, thereby cutting off communication of the port 18 with the exhaust 37 and compression begins.

At the same time with the compression of the air in the cylinder piston, the fuel oil in the chamber 30 of the pump is also compressed and is in this compressed form injected past the check valve 29, see Fig. 3, through the conduit 27 into the cylinder piston. In Fig. 1 to the right it will be noticed that at the highest compression between the inner piston 11 and the cylinder piston 6, the chamber 30 in the pump is also under highest compression caused by the pump piston 24.

The explosion in the cylinder piston and the moving of the cylinder-piston outwardly cause also the sliding of the pump piston 24 outwardly, resulting in an expansion or suction on one side of the pump piston, the chamber 30, thereby filling the chamber with new fuel oil; and resulting also in a compression at the other side of the pump piston, the chamber 31, thereby causing the water accumulated in the chamber 31 to pass through the conduit 26 in the pump-piston rod into the cylinder piston. As the gas in the cylinder piston in this position has just exploded, it is highly heated and the water spray injected by the pump will be expanded and vaporized into steam. The vapor created is also of importance in using low-gravity fuel oil.

For starting the engine, it will easily be understood that better fuel oil can be injected through the connections 19 on the housings.

In connection with my engine, I prefer to

use a spark plug as illustrated in Fig. 4, the numeral 38 indicating the material in the cylinder piston, while the numeral 39 indicates the material in the housing.

65

The spark plug is constructed in two halves, one of which is secured to the cylinder piston and the other is secured to the housing. A steady current is supplied to the stem 40. This would naturally cause a permanent spark, but as the stem is insulated by the insulation 41 from the metal, no spark can occur until the stem 40 passes over the pin 42 in the second half of the spark plug. This pin is also insulated from the metal, in this case by the insulation 43, and sparking can occur only between the bent pin 44 and the lower end 45 of the pin 42.

70

Having thus described my invention, I claim:—

80

1. In internal combustion engines having a housing a cylinder piston slidably mounted within the housing, a feeding pump secured to the housing, the piston rod of the feeding pump secured to the cylinder piston and constituting means whereby the contents of the feeding pump is delivered to the inside of the cylinder piston.

85

2. In internal combustion engines having a housing: A compressor, a cylinder piston slidably mounted in the compressor, an inner piston slidably mounted within the cylinder piston, a feeding pump secured to the housing, a piston slidably mounted within the feeding pump, a piston rod secured at its one end to the piston within the feeding pump and at its other end to the cylinder piston, a conduit from the chamber at the one side of the piston within the feeding pump through the feeding pump piston rod communicating with the inside of the cylinder piston, a ball check valve controlling the passage of air, fuel or liquid through the conduit, a conduit from the chamber at the other side of the piston within the feeding pump through the feeding pump piston rod communicating with the inside of the cylinder piston, a ball check valve controlling the passage of air, fuel or liquid through the conduit, grooves in the inner surface of the housing and grooves and ports in the cylinder piston wall co-acting to form a bypass from the compressor in the housing to the inside of the cylinder piston at the time of highest compression in the compressor.

90

In testimony whereof I hereunto affix my signature in the presence of two witnesses.
